UNITED STATES PATENT OFFICE.

ANTOINETTE M. WINTER, OF BUTTE, MONTANA.

DARNER.

1,172,186.

Specification of Letters Patent. Patented Feb. 15, 1916.

Application filed March 12, 1915. Serial No. 13,829.

To all whom it may concern:

Be it known that I, ANTOINETTE M. WINTER, a citizen of the United States, residing at Butte, in the county of Silverbow and State of Montana, have invented new and useful Improvements in Darners, of which the following is a specification.

The invention relates to a darning device, and more particularly to the class of hosiery and glove darners.

The primary object of the invention is the provision of a darning device of this character wherein neat stitching can be made on the fingers of gloves or on hosiery for the darning thereof irrespective of the sizes of the same, the darning being readily and easily adjusted for this purpose.

Another object of the invention is the provision of a darning device of this character which is of novel form so that it may be used for the two-fold purpose of darning either clothes or hosiery in an easy and convenient manner.

A further object of the invention is the provision of a darning device of this character which is simple in construction, neat in appearance, readily and easily adjusted, strong, durable, and inexpensive in manufacture.

With these and other objects in view, the invention consists in the construction, combination and arrangement of parts as will be hereinafter fully described, illustrated in the accompanying drawing, and pointed out in the claim hereunto appended.

In the drawing: Figure 1 is a side elevation of a darning device constructed in accordance with the invention. Fig. 2 is a vertical longitudinal sectional view thereof. Fig. 3 is a sectional view on the line 3—3 of Fig. 1. Fig. 4 is a sectional view on the line 4—4 of Fig. 1.

Similar reference characters indicate corresponding parts throughout the several views in the drawing.

Referring to the drawing in detail, the darning device comprises a substantially egg-shaped body 5 which is designed for a darning ball to be used in darning hosiery, and integral or fixed to the smaller end of the said body 50 is a stem or arm 6 which slightly tapers toward its free end to serve as a handle for the body 5 or a spreader arm for the finger of a glove, and is adapted to coöperate with a hollow or channeled arm 7 which carries 55 a bowl 8, the same being shaped correspondingly to one-half of the body 5 and is adapt-

ed to coöperate therewith to vary the size of the same when used for darning different sizes of hosiery, while the members 6 and 7 are adapted for use in stitching or darning the fingers of gloves. Passed through the arms 7 contiguous to the bowl 8 is an adjusting screw 9, the same being also passed through the stem or arm 6 and has threaded thereon a nut 10 which is countersunk within the said arm 6, the screw 9 being formed with an externally knurled head 11 so that it can be readily turned for the adjustment thereof. Arranged between the arms 6 and 7 is a bowed leaf spring 12, the ends of which act against the arms 7 and the bowl 8 so that on the loosening of the screw 9 the parts of the darning device will be separated for expanding the same to properly fit hosiery or the fingers of gloves of larger sizes to permit the neat repairing thereof by the stitching or darning of the same in the usual well-known manner.

In the use of the darning device, the arms 6 and 7 are inserted in the finger to be repaired of the glove, and on pressing upon the body 5 and the bowl 8 the said arms will be spread apart under the tension of the spring 12 for the stretching of the finger of the glove, and thereby permit the neat darning or stitching of the same. Now, in the use of the darning device for hosiery, the screw 9 is adjusted so that the body 5 and the bowl 8 will afford the proper area to fit within the hosiery so as to stretch or hold the portion thereof to be darned taut, and the darning or stitching of the same is executed in the usual well-known manner.

From the foregoing description, taken in connection with the accompanying drawing, the construction and manner of operation of the device will be clearly understood, and therefore a more extended explanation has been omitted.

What is claimed is:—

A darning device comprising a substantially egg-shaped body having an outwardly tapered arm integrally formed with the smaller end thereof, said arm being provided with a cut-away portion adjacent to the smaller end 105 of the body to provide a flat surface, an inwardly arched spring fixed medially thereof to the flat surface, a channeled arm having a bowl, the said arm and bowl being correspondingly shaped to substantially one-half of the first-named arm and body respectively to receive the same, a nut embedded 110

in the first-named arm, and a headed set screw passed through both of said arms and spring and adjustably engaged in the nut to resist the action of the said spring for the 5 bringing of the first-named arm and body and the second named arm and bowl toward each other.

In testimony whereof I affix my signature in presence of two witnesses.

ANTOINETTE M. WINTER.
